UNITED STATES PATENT OFFICE.

DANIEL DAVIS, OF ELMIRA, NEW YORK.

VICE.

SPECIFICATION forming part of Letters Patent No. 271,316, dated January 30, 1883.

Application filed October 16, 1882. (No model.)

To all whom it may concern:

Be it known that I, DANIEL DAVIS, a citizen of the United States, residing at Elmira, in the county of Chemung and State of New York, have invented certain new and useful Improvements in Vises; and I do hereby declare that the following is a full, clear, and exact description of the same, reference being had to the annexed drawings, making a part 10 of this specification, and to the letters and figures of reference marked thereon.

Figure 1 of the drawings is a perspective view of my invention; Fig. 2, a longitudinal vertical section of the same, and Fig. 3 a detail sectional view of one of the jaws.

This invention relates to certain new and useful improvements in vises, either for the use of iron or wood workers; and the object thereof is to produce such a vise whereby 20 the long screw common to vises in general use is dispensed with and an instantaneous adjustment obtained without changing hands, the work being held in one while the adjusting and clamping are performed with the other hand, without letting go of either, and by the 25 simplicity of construction and arrangement of the several parts a vise of my description is as readily and cheaply manufactured as those in common use, and by its ready adjustability is 30 far preferable. These objects I attain by the construction substantially as shown in the accompanying drawings and hereinafter described.

In the drawings, A B represent the jaws of 35 a vise similar in appearance to those of the ordinary manufacture, but differing in construction. The front jaw, A, is provided with a recess, a, cored out to receive the front end of a sliding bar, C, constructed preferably of 40 wrought or malleable iron and tapped to receive a short screw, D. This screw has near its end a smooth extension, b, terminating in a screw-threaded nipple, c, which passes through a slide, E, working in a suitable slot, d, in the 45 sliding bar C, the inner end of the nipple being provided with a nut, e, to prevent the slide E from moving ahead, and at the same time holds the head of the screw snugly against the front jaw, A. The slide E is provided 50 upon each side with projecting tenons f, which receive the upper ends of lugs or braces F. The

lower ends of these braces, entering the recess a in the front jaw, are held in place by a pin, g, passing through said lugs or braces, and headed upon the exterior sides of the said jaw. 55 The jaw A, upon the interior sides of the recess a, is provided with shoulders h just over the lugs or braces F, said shoulders extending down on the same angle thereof to hold these lugs or braces in position, and also to keep the 60 jaw from pitching forward when the vise is being unscrewed. The sliding bar C is provided with a ratchet-plate, G, recessed in the bottom thereof and extending its entire length, said ratchet-plate being preferably of steel, with 65 the teeth thereon finely cut, in order to admit of a nicety of adjustment. This ratchet-plate G engages with a short ratchet, H, recessed in the rear jaw, B, near its front end, said jaw being constructed to allow of the sliding bar 70 C, provided with the ratchet-plate G, sliding therein, and also admit the lugs or braces F entering therein, the opening in which works this sliding bar being of sufficient depth to allow of the same being raised or lifted out of 75 the ratch.

While I have described the ratchet-plate as engaging with a short ratchet recessed in the rear jaw, it is obvious that a pawl may be used instead of such ratchet, if desired. 80

The operation of my invention is as follows: To open the vise, lift the front jaw, A, until the ratchet-plate G upon the sliding bar C comes clear of the ratchet H in the rear jaw, B, when said sliding bar can be drawn out the required 85 distance for the insertion of the work between these jaws, the sliding bar being pushed back or inwardly without lifting. After the work has been placed between the jaws A B the screw D is turned so as to cause the slide E, 90 having the lugs or braces F tenoned thereto, to work in the slot d, thereby drawing the front jaw toward the rear, while the ratchet or pawl H holds the sliding bar C firmly in the position already attained, thereby clamping 95 the work firmly between the jaws in a quick and thorough manner, without the necessity of making but a few turns of the screw. Thus it will be seen that the tighter the jaw A is screwed up to the jaw B the less tension there 100 is upon the ratchet-plate, as a great portion of the strain is downward, causing the strain to

bear in the bottom of the ratchet at an angle of about forty-five degrees instead of on the teeth of the ratchet.

Having now fully described my invention, 5 what I claim as new, and desire to secure by Letters Patent, is—

1. In a vise, the ratcheted and slotted and threaded sliding bar C, ratchet H, and screw D, in combination with the slide E, lugs or 10 braces F, and jaw A, substantially as and for the purpose specified.
2. In a vise, the jaw A, formed with the re-

cess *a* and angular shoulders *b*, in combination with the braces F, the ratchet and slotted sliding bar C, slide E, and nut *e*, substantially 15 as and for the purpose described.

In testimony that I claim the above I have hereunto subscribed my name in the presence of two witnesses.

DANIEL DAVIS.
